UNITED STATES PATENT OFFICE.

JACOB B. ERHART, OF AUBURN, NEW YORK.

RUB-IRON FOR VEHICLES.

SPECIFICATION forming part of Letter's Patent No. 738,990, dated September 15, 1903.

Application filed June 26, 1903. Serial No. 163,207. (No model.)

To all whom it may concern:

Be it known that I, JACOB B. ERHART, of Auburn, in the county of Cayuga, in the State of New York, have invented new and useful 5 Improvements in Rub-Irons for Vehicles, of which the following, taken in connection with the accompanying drawings, is a full, clear, and exact description.

This invention relates to improvements in 10 rub-irons for vehicles, against which the steering-wheels are adapted to contact to prevent injury to the body and tires of the vehicles.

The object of this invention is to provide a 15 roller rub-iron and to mount the same in such manner that when it is engaged by the wheels of the vehicle and rotated the friction and consequent noise and wear will be reduced to a minimum.

Another object is to support the roller at 20 its opposite ends only and to provide means for taking up the wear of the roller-bearings.

Other objects will be brought out in the following description.

In the drawings, Figure 1 is a perspective 25 view of the detached rub-iron or roller and its supporting bracket. Fig. 2 is a side elevation of the parts seen in Fig. 1, the ends of the roller and its bearings being shown in section. Fig. 3 is a sectional view taken on line 3-3, Fig. 2. Fig. 4 is a perspective view of the detached roller rub-iron, showing one of its trunnions detached. Fig. 5 is a perspective view of the detached bracket for supporting the roller rub-iron. Fig. 6 is a perspective view of one of the tapering bushings 30 for receiving the roller-bearings.

Similar reference characters indicate corresponding parts in all the views.

This invention consists, essentially, of a 40 bracket or metal plate 1, carrying a rotary cylindrical rub-iron or roller 2. The bracket 1 consists of a flat metal body 3, which is adapted to be secured to the under side of the frame of the body of the vehicle and is 45 formed with lengthwise slots 4 to receive suitable clamping screws or bolts, (not shown,) but are fastened to the frame of the body, so that when the bracket is secured in position the slots permit it to be adjusted longitudinally to bring the rub-iron in proper relation to engage the wheels. One of the lon-

gitudinal edges of this plate is cut away at the center for forming a recess 5 to receive the roller 2, the opposite ends of said longitudinal edge being provided with cylindrical or tubular arms 6, having alined threaded openings 7 extending therethrough from end to end. These openings 7 are tapered inwardly toward each other from their outer ends for receiving tapering split bushings or 60 bearings 8, as best seen in Fig. 6, said bushings being threaded exteriorly and are provided with transverse slots 9 in their outer ends for receiving a suitable tool, as a screwdriver, and whereby the bushings may be 65 adjusted longitudinally when desired. Each of these bushings is formed with a longitudinal slit 10, extending outwardly from its inner end face, but only part of its length, so that when the tapering bushing is screwed inwardly the opposite jaws formed by the longitudinal split are compressed upon the roller-bearings, presently described, to take up any 70 wear. These bushings are provided with lengthwise sockets 11, which extend outwardly from their inner ends, but only partially through the same, the outer ends or heads being solid, although it is apparent that the openings may extend entirely through the bushings, if desired, the object 75 of closing the outer ends being to prevent the entrance of dust or dirt to the bearings.

The roller rub-iron 2 is interposed between the tubular arms 6 and is of substantially the same length as the distance between the inner 80 end faces of said tubular arms, and the opposite ends of said roller rub-irons are provided with sockets 12, extending inwardly from their end faces for receiving the inner ends of suitable trunnions 13. The outer ends of the sockets 12 are enlarged at 14, and the intermediate portion of the trunnions 13 are also enlarged for forming an annular flange 15.

The inner ends 16 of the trunnions 13 are driven with a tight fit into the sockets 12 95 until the shoulders or flanges 15 enter the recesses 14 and engage the inner end walls of said recesses, so that it is apparent that when these trunnions are placed in operative position they are fixed to and become a part of 100 the roller rub-iron 2 to rotate therewith. The trunnions 13 extend beyond the end faces

of the roller rub-iron 2 into the open ends of the bushings 8 and are formed of less diameter than the interior diameter of the bushings to receive roller-bearings 17, which are 5 interposed between the trunnions 13 and inner surfaces of the bushings to form roller-bearings for the rub-iron and to reduce the friction incidental to its rotation to a minimum. The inner ends of the bushings 8 preferably 10 extend a slight distance beyond the inner end faces of the tubular arms 6 and enter the recesses 14, so as to prevent as much as possible the entrance of dust to the bearings.

In assembling the rub-iron upon the bracket 15 1 the cylindrical part 2 is first placed between the tubular arms 6, and the trunnions or studs 13 are then driven into the sockets 12 through the openings 7, after which the bushings 8, with their roller-bearings 17, are screwed into 20 their sockets 7, with the rollers 17 surrounding the trunnions 13, the bushings being properly adjusted to permit the free rotation of the rub-iron without undue play.

Having thus described my invention, what 25 I claim, and desire to secure by Letters Patent, is—

1. In a rub-iron for vehicles, a bracket having alined openings, tapering bushings inserted in said openings and split longitudinally, and a roller having its opposite ends journaled in said bushings.

2. A rub-iron for vehicles comprising a bracket having tubular arms threaded interiorly, tapering threaded bushings inserted 35 in said tubular arms and split longitudinally, and a roller rub-iron having its opposite ends journaled in said bushings.

3. In a rub-iron for vehicles, a bracket having tubular arms, bushings inserted in said 40 tubular arms and extending beyond their inner faces, and a roller between said arms and

having their outer ends encircling the inwardly-projecting ends of the bushing.

4. A rub-iron for vehicles comprising a bracket having tubular arms threaded interiorly, tapering threaded bushings screwed into said tubular arms and split longitudinally through portions of their lengths, the inner ends of the bushings projecting beyond the inner faces of the irons, and a roller rub-iron between the arms and encircling the inner ends of the bushings.

5. A rub-iron for vehicles comprising a bracket having tubular arms threaded interiorly, tapering threaded bushings screwed into said tubular arms and split longitudinally through portions of their lengths, the inner ends of the bushings projecting beyond the inner faces of the irons, a roller rub-iron between the arms and encircling the inner ends of the bushings, trunnions projecting from the ends of the roller into the bushings, and roller-bearings between the trunnions and inner surfaces of the bushings.

6. A rub-iron for vehicles comprising a bracket having tubular arms threaded interiorly, threaded bushings screwed into said arms and having sockets extending outwardly from their inner end faces, but only part way through the bushings, said bushings having 70 their inner ends extending beyond the inner faces of the arms, and a roller rub-iron between the arms having its opposite ends encircling the inwardly-projecting ends of the bushings and provided with trunnions journaled in said sockets.

In witness whereof I have hereunto set my hand this 18th day of June, 1903.

JACOB B. ERHART.
